(57) **CLAIM**

The ornamental design for a touch screen table, as shown and described.

DESCRIPTION

FIG. 1 is a front, right perspective view of the touch screen table showing our new design in a first state in which the screen faces upward to be used as a touch screen;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view thereof in a second state in which the screen is shown in front of a user and allows the user to watch content like a television;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right perspective view thereof in a third state in which the screen faces downward to be used as a desk;

(Continued)

FIG. 16 is a front view thereof;
 FIG. 17 is a rear view thereof;
 FIG. 18 is a left side view thereof;
 FIG. 19 is a right side view thereof;
 FIG. 20 is a top plan view thereof; and,
 FIG. 21 is a bottom plan view thereof.
